(57) **CLAIM**

The ornamental design for a sun visor mounting system, as
shown and described in FIGS. 1-11.

DESCRIPTION

FIG. 1 is a front, top and right side perspective view of a sun
visor mounting system;

FIG. 2 is a rear, bottom and left side perspective view
thereof;

FIG. 3 is a top plan view thereof;

FIG. 4 is a bottom plan view thereof;

FIG. 5 is a front perspective view thereof;

FIG. 6 is a rear perspective view thereof;

FIG. 7 is a front, bottom and left side perspective view
thereof;

FIG. 8 is a left, top perspective view of a joining plate of the
sun visor mounting system;

FIG. 9 is a bottom, right side perspective view of an
extension plate of the sun visor mounting system;

FIG. 10 is a rear perspective view of a mounting plate of the
sun visor mounting system;

FIG. 11 is a top, left side perspective view thereof;

FIG. 12 is a rear, right side and bottom perspective view
thereof, shown in an environment of use; and,

FIG. 13 is another rear, right side and bottom perspective
view thereof, shown in an environment of use.

The break lines shown throughout the sun visor mounting
system in the Figures indicate that the appearance of any
portion of the article between the break lines forms no part
of the claim design.

The broken lines in FIGS. 1-11 illustrate portions of the sun
visor mounting system that form no part of the claimed
design.

The broken lines illustrating the vehicle, radar detector,
monitor, and wires shown in FIGS. 12 and 13 illustrate
environment which form no part of the claimed design,
while the remaining broken lines illustrate portions of the
sun visor mounting system that forms no part thereof.
